Wimpy M. Brooks

BY

W. H. Decker
ATTORNEY

UNITED STATES PATENT OFFICE.

WINFRED M. BROOKS, OF SOUTH ORANGE, NEW JERSEY.

SEALING MEANS.

Application filed June 12, 1923. Serial No. 644,831.

To all whom it may concern:

Be it known that I, WINFRED M. BROOKS, a citizen of the United States, and a resident of South Orange, in the county of Essex 5 and State of New Jersey, have invented certain new and useful Improvements in Sealing Means, of which the following is a specification.

This invention relates to self-locking 10 seals of the character shown in U. S. Letters Patent No. 1,137,183 of April 27, 1915.

In that patent is disclosed a construction in which a member is bent into loop form at its central portion with the free ends 15 thereof crossing each other to provide a main leg and a subsidiary leg. Subsequently the main leg is coiled around the subsidiary leg after the element to be sealed has been inserted within the loop. The 20 main leg is provided with weakening notches at the point where it crosses the subsidiary leg so that if it is attempted to uncoil the main leg the metal becomes fractured.

It has been found that if the initial coiling operation has been carelessly performed 25 the bending operation does not always take place substantially at right angles to the notches and consequently the initial bending of the metal does not weaken it sufficiently to produce a break when an attempt is subsequently made to unbend it. Also, in opening 30 the seal to insert the hasp or other element to be sealed, the parts, by careless handling, become distorted and the main leg is therefore not always bent during the 35 subsequent coiling operation as nearly as possible in its own plane with the result that the subsidiary leg extends unduly and can be used as a lever enabling the seal to 40 be opened.

The main object and feature of this invention is to provide means whereby these difficulties may be overcome, and the invention consists of the hereinafter described 45 features of construction, a preferred embodiment of which is disclosed in the accompanying drawings.

In said drawings:

Fig. 1 is a view in elevation of a self-locking seal embodying the invention.

Fig. 2 is a view similar to Fig. 1 showing the arrangement of the parts after the subsequent coiling operation has been performed.

Fig. 3 is a sectional view on the plane of line 3—3 of Fig. 1.

Fig. 4 is a sectional view on the plane of line 4—4 of Fig. 2.

Figs. 5 and 6 illustrate modifications of the invention.

As shown in Fig. 1, the sealing member is made out of a piece of wire bent into a loop by crossing the ends thereof substantially at right angles to each other to provide a main leg 1 and a subsidiary leg 2. 3 indicates transverse notches in the main leg located at the point where it crosses the subsidiary leg, and 4 is a flattened portion on the opposite side of the main leg. The provision of this flattened surface 4 directs 65 the subsequent bending of the main leg substantially at right angles to the plane of the notches so that the metal is properly weakened by the bending operation. In the drawings 5 indicates the coil formed by the 70 subsequent bending operation of the main leg.

In order to direct the coiling of the main leg as near as possible in its own plane 75 over the subsidiary leg there are provided 80 suitable confining means on the subsidiary leg. These means may take many forms. In Figs. 1 to 4 inclusive are provided a flattened surface 6 and another flattened surface 7 at opposite sides of the point where 85 the main leg crosses the subsidiary leg. In Fig. 5 the subsidiary leg is provided with an offset portion 8 and a flattened surface 7, and in Fig. 6 the subsidiary leg is provided with an offset and weakened portion 9 and a flat surface 7.

I claim:

1. A sealing element comprising: a wire bent into a loop by crossing the ends thereof substantially at right angles to each other 95 to provide a main leg and a subsidiary leg, said main leg having transverse notches on one side and a flattened surface on its opposite side at the point where it crosses the subsidiary leg to thereby direct subsequent 100 bending of the main leg substantially at right angles to the plane of the notches.

2. A sealing element comprising: a wire bent into a loop by crossing the ends thereof substantially at right angles to each other 105 to provide a main leg and a subsidiary leg, said main leg having transverse notches on one side and a flattened surface on its

opposite side at the point where it crosses the subsidiary leg to thereby direct subsequent bending of the main leg substantially at right angles to the plane of the notches 5 and said subsidiary leg having confining means at opposite sides of the point where the two legs cross each other to thereby

direct subsequent coiling of the main leg as near as possible in its own plane.

Signed at New York city in the borough 10 of Manhattan, county and State of New York.

WINFRED M. BROOKS.
